Malcolm C. Davis, Jersey City, N. J.

Application August 7, 1946, Serial No. 132,336

Term of patent 3½ years

(Cl. D58—26)

To the Commissioner of Patents:

Be it known that I, Malcolm C. Davis, a citizen of the United States and a resident of Jersey City, in the county of Hudson and State of New Jersey, have invented a new, original, and ornamental Design for a Jewelry Holder, of which the following is a specification, reference being had to the accompanying drawings, forming part thereof.

In the drawings:

Fig. 1 is a side view of a jewelry holder embodying my new design.

Fig. 2 is a top plan view thereof.

Fig. 3 is a view in front elevation.

Fig. 4 is a view in rear elevation.

I claim:

The ornamental design for a jewelry holder, substantially as shown.

MALCOLM C. DAVIS.
